GRINDROD KERSHAW, OF WHITWORTH, ROCHDALE, ENGLAND

TUBE HOLDER

Application filed December 20, 1928, Serial No. 327,877, and in Great Britain December 21, 1927.

This invention of improvements in or relating to spindles or holders for paper or other cones or tubes for machinery for winding yarn, thread, cord, twine and the like, relates to spindles or holders of the kind comprising or provided with parts expandable and contractible in diameter or movable outwards and inwards, away from and towards the axes or center lines of the spindles or holders for engaging and releasing paper or other cones or tubes on the spindles or holders and to devices providing parts movable outwards and inwards relatively to the axes or center lines of such spindles or holders for holding and releasing paper or other cones or tubes thereon and means for operating such devices.

This invention consists in part in plates or whorls formed wholly or in part of resilient or flexible metal which present on or by their circumferential parts edges or teeth adapted to engage with the inner sides of paper or other cones or tubes and are adapted to be changed throughout or in part from or to a flat or less bulged, dished or bent condition to or from a bulged, dished or bent or more bulged, dished or bent condition and from or to a greater to or from a less diametral extension and are applied in or to spindles or holders for paper or other cones along with means by which the central parts or parts of the plates or whorls between the central parts and the circumferences may be moved or allowed to move in the direction of the axes or center lines of the plates or whorls relatively to the circumferential parts according to the formation of the spindles or holders and the manner in which the plates or whorls are employed so that the plates or whorls are enabled to engage or made to release paper or other cones or tubes on the spindles or holders.

Exemplificatory forms of plates or whorls provided according to this invention are shown in the accompanying drawings in all the figures of which the same reference characters are employed to indicate corresponding parts. Figs. 1 and 2 are a side elevation and diametrical section of one plate or whorl provided according to the invention when unstressed, Fig. 3 is a side elevation and Figs. 4

and 5 are different diametrical sections taken respectively on the planes indicated by the lines A A and B B of Fig. 3 showing another plate or whorl provided according to the invention in the stressed condition in which it is also represented in Figs. 7 and 8 to be mentioned later herein. Fig. 6 is a side view of a third form of a plate or whorl. Fig. 7 is a longitudinal section with some parts shown in side elevation showing one form of spindle or holder furnished with a plate or whorl of the form shown in Figs. 3, 4 and 5. Fig. 8 is an end view of some parts shown in Fig. 7 seen in the direction of the arrow G indicated in Fig. 7. Fig. 9 is a longitudinal section with some parts shown in side elevation showing one form of spindle or holder furnished with a plate or whorl of the form shown in Figs. 1 and 2. Fig. 10 is an end elevation of the spindle or holder shown in Fig. 9. Fig. 11 is a longitudinal section with some parts shown in side elevation showing one form of spindle or holder furnished with two plates or whorls for holding a cylindrical tube and Fig. 12 is a transverse section taken on the plane indicated by the line D D of Fig. 11. Fig. 13 is a longitudinal section with some parts shown in side elevation showing another form of spindle or holder with two plates or whorls for holding a cylindrical tube.

Figs. 1 and 2 show a plate or whorl α with a flat substantially circular central portion α' and eight equal radial arms α^2 dished or bent so that the radiating arms α^2 when the plate or whorl is unstressed extend to one side of the plane of the central part α' in the shape of part of a frustum of a hollow cone.

Figs. 3, 4 and 5, show in the stressed and therefore dished or bent condition in which it is also shown in Figs. 7 and 8 hereinafter to be described, a plate or whorl α differing from that shown in Figs. 1 and 2 in that the radiating arms α^{2*} are made of two lengths, the longer α^3 alternating with the shorter α^4 that the plate or whorl when unstressed is flat and that the central hole is larger.

When the plate or whorl α shown in Figs. 3, 4 and 5 is subjected to lateral stress so that the fingers or arms α^{2*} are bent from the flat

condition to one side or face of the plate or whorl to retract the arms and so to reduce the diametral extent of the plate or whorl a and a paper or other cone is applied around the 5 plate or whorl a in contact with the ends of the longer fingers or arms a^3 and the plate or whorl a is set free to return less or more completely towards the unstressed condition, the longer arms or fingers a^3 will become en- 10 gaged with the inner surface of the paper or other cone and be held thereby from returning completely to the unstressed condition and the stress to which the longer arms or fingers a^3 remain subject will be transmitted 15 to the shorter arms or fingers so that they will be made to bear on any surface presented to them as an abutment enabling the longer arms or fingers a^3 to keep the paper or other cone pulled in one direction. 20 Fig. 6 shows a whorl or plate a in which four radiating arms a^{2**} are made each to furnish a longer and shorter radiating projection a^{3*} , a^{4*} and so present projections corresponding to the alternate longer and 25 shorter radiating arms a^3 , a^4 of the plate or whorl shown in Figs. 3 and 4.

One illustrative embodiment of a plate or whorl a applied according to the invention will be described in reference to Figs. 6 and 7 30 as applied in or to a spindle or holder b with larger and smaller conical parts b' , b^2 at its ends for application of a paper or other cone c and mounted in a well known way of mounting cone spindles or holders in winding machines to revolve about an axis or stud d unrevolvable but pivoted or connected by a stud e to a movable arm f furnished with cam surfaces f' available for effecting the disengagement of engaging devices from cones applied 35 on the spindle or holder b in such a way that the stud or axle d can be moved towards and away from a winding drum and turned about one end or part into and out of a position in which it is held by a detent spring, not shown, 40 for revolution of the holder b and winding of yarn on a cone c thereon and out of and into position for the application and removal of cones c . In the illustrative embodiment of a plate or whorl as illustrated in Figs. 6 and 50 7, a plate a of resilient or flexible metal of the form illustrated in Figs. 3 and 4 presenting longer arms a^3 and alternate shorter arms a^4 extending from a central collar a' connecting them so far as to present with the longer 55 arms a^3 , a diametral extent suitably greater than that of the larger end b' of the spindle or holder b and presenting with the shorter arms a^4 a diametral extent equal to or a little less than that of the larger end b' of the spindle or holder b , is mounted loose upon a collar or boss b^3 forming part of the spindle or holder b and surrounding the axle or stud d so that the plate a is between the larger end 60 of the spindle or holder b and a sleeve or collar g loose upon the axle or stud d and movable

lengthwise thereof by means of the cam faces f' on the movable arm f . So long as the sleeve or collar g is not made to press against the plate or whorl a and their arms or fingers a^2 are free to maintain their full outward extension the plate or whorl a will remain flat. When the stud or axle d is turned into position for a cone c to be applied to or to be removed from the spindle or holder b the sleeve or collar g will be made to press against the plate a and being made to press it against the larger end of the part b' of the spindle or holder b , which as usual presents a hollow h , will press the central part into that hollow h and retract the ends of the longer arms a^3 so as to reduce the diametral extent to a little less than or approximate equality with that of the larger end of the part b' of the spindle or holder b and also bend the shorter arms a^4 in the same or nearly the same direction as the longer arms a^3 . When after the application of a cone c on the spindle or holder b the stud or axle d is turned into position for the revolution of the spindle or holder b , that is to say into the position in which it is indicated in Fig. 7, and the winding of yarn thereon, the plate a will be relieved of the pressure of the sleeve or collar g and so set free to be revolved about or relatively to the stud or axle d and the ends of its arms a^3 90 will engage the inner side of the cone c in position on the spindle b and secure the plate in position in the cone c .

When the plate a is pressed by means of the collar g into the hollow h so pressing the plate a into a dished or hollowed form, the longer arms a^3 and the shorter arms will both be pressed against the larger end of the part b' and so be made to form approximately parts of the same frustum of a cone and afterwards when the plate a is relieved of the pressure of the collar g and tends to return to its normal flat form in the parts formed by the arms a^3 , a^4 the resilience of the plate a will cause the shorter arms a^4 to remain pressing against the larger end of the part b' while the longer arms engaging the cone c and tending to move further away from the larger end of the part b' will tend to pull the cone c on to the spindle or holder b . The larger end of the part b' is advantageously bevelled as shown to prevent the longer arms a^3 of the plate a from rocking upon it and moving their outer ends towards the smaller end of the spindle or holder b when the plate a is resuming or tending to resume its flat form.

Another illustrative embodiment of a plate or whorl provided according to this invention will be described in reference to Figs. 9 and 10 as applied in or with a spindle or holder for paper or other cones which comprises an axle i adapted to be revolved in bearings or guides, and two conical sleeves j , k , one larger than the other and advan- 125 130

tageously one or both adjustable along and secured in position upon that axle *i* for example as shown in the case of two adjustable conical sleeves *j*, *k*, by the one conical part *k* 5 being formed with a central hole to receive the axle *i* and a screw threaded hole furnished with a set-screw *l* for securing it in position and the other *j* being formed with a screw-threaded central hole in order to be screwed 10 into position on a screw-threaded part *i'* of the axle *i* and another screw-threaded hole furnished with a set-screw *m* for fixing it after it has been screwed into position. In this embodiment of a plate or whorl *a* so 15 applied, a plate or whorl of the form illustrated in Figs. 1 and 2 and presenting arms *a*² extending from a central collar *a'* connecting them and formed with a central hole so that it may be passed freely on to the screw-threaded part *i'* of the axle *i* is dished or 20 bent so that the arms *a*² extend obliquely from one face of the collar *a'* and in the unstressed condition of the plate or whorl *a* present a diametral extent a little less than or 25 approximately equal to that of the larger face of the conical sleeve *j*. The plate or whorl *a* is placed on the axle *i* in position for the obliquely extending arms *a*² to bear against the larger face of the larger conical sleeve *j* 30 which conveniently is bevelled as shown near the edge to receive bearing of the arms *a*². A washer or collar *n* placed around the axle *i* is provided to be pressed advantageously by means of a nut *o*, advantageously a wing-nut, 35 screwed upon the screw-threaded part *i'* of the axle *i* so that by the plate or whorl *a* being made flatter the outer ends of the arms *a*² can be pressed into engagement with a paper or other cone or tube *c* applied around 40 the conical sleeves *j*, *k*. In this case the plate or whorl *a* in being pressed into engagement with a paper or other cone or tube *c* will tend to pull it further onto the conical sleeves *j*, *k* by the arms *a*² being made to rock upon 45 the parts of the sleeve *j* upon which they bear.

In the application of this invention to or in spindles or holders for cylindrical tubes, two plates or whorls formed, applied and used 50 generally as aforesaid are provided in or with each spindle or holder, as for example in illustrative embodiments, pairs of discs or bosses corresponding to the larger ends of the larger conical parts of the spindles or 55 holders already described as illustrative embodiments or the ends of cylinders each corresponding to two of such discs or bosses are provided on axles or other parts to or with which plates or whorls are applied in modes 60 generally corresponding to those hereinbefore described.

Figs. 11 and 12, showing a spindle or holder for cylindrical tubes, show a spindle or holder comprising an axis or stud *d* to 65 be turned about a stud *e* in a movable arm *f* with cam surfaces *f*¹ mounted similarly to that shown in Fig. 7. In Figs. 11 and 12 a sleeve *p* is mounted upon the axis or stud *d* and adapted to be revolved around it. The sleeve *p* which externally is mainly cylindrical and formed at one end with a larger part *p*¹ presenting a conical surface *p*² at one end is held against longitudinal movement by means of pegs *q* screwed into the larger part *p*¹ and made to engage a groove *d*¹ in the stud or axis *d*. The sleeve *p* is formed internally with annular grooves and recesses *r*, *s*, *t*, to hinder the escape of lubricant supplied to the surface of the axis or stud *d* by means of a longitudinal hole *d*² 70 with radial branches formed in the axis or stud *d*. Around the sleeve *p* is mounted another sleeve *u* capable of a longitudinal movement on the sleeve *p*. The sleeve *u* is adapted to bear at one end against the conical surface *p*² and at that end is provided with a collar *u*¹ to be brought against the cam surfaces *f*¹ in order that the sleeve *u* may be moved lengthwise of the sleeve *p* away from the conical surface *p*² when the axis or stud *d* is turned into position for a tube to be applied to or removed from the holder and is also provided with a collar *u*² and a cylindrical part *u*³ extending from that collar *u*². 75 A plate or whorl *a* similar to that shown in Figs. 3, 4 and 5 and to that described with reference to Figs. 7 and 8 is mounted around the cylindrical part *u*³ of the sleeve *u* and made to present one face to the collar *u*². Around the sleeve *u* is applied a cylindrical collar *v* presenting an annular hollow *w* and circumferentially bevelled edge for presentation to the plate or whorl *a* and corresponding to those of the sleeve *b* shown in 80 Figs. 7 and 8. Pegs *x* screwed into the collar *v* and made to pass through slots in the sleeve *u* and to enter holes in the sleeve *p* hold the collar against longitudinal movement and turning relatively to the sleeve *p* and also hold the sleeve *u* against turning on the sleeve *p*. 85 Another plate or whorl *a* similar to that applied around the sleeve *u* but with a smaller central hole is mounted around the sleeve *p* and made to present its dished or hollowed face to the end of the cylindrical part *u*³ of the sleeve *u* and another cylindrical collar *y* generally similar to the collar *v* but with a smaller central hole is secured by set-screws *z* to the sleeve *p*. The collars *v*, *y* are 90 secured to the sleeve *p* in such position that when the axis or stud *d* is in the position in which it is shown in Fig. 11 and the arms or fingers *a*² of the plates or whorls *a* are free to maintain their full outward extension the plates or whorls *a* maintain their flat form but when the axis or stud *d* is turned about the axis of the stud *e* connecting it to the arm *f* the collar *u*¹ of the sleeve *u* being made to bear against the cam faces *f*¹ will 95 be forced away from the conical surface *p*² 100 105 110 115 120 125 130

and be made to press the plates or whorls α into the hollows w of the collars v, y so as to retract the arms α^2 and thus to reduce the diametral extents of the plates or whorls α to a little less than or approximate equality with those of the collars v, y . Consequently as in the case of the holder or spindle shown in and described with reference to Figs. 6 and 7, when the stud or axis d has been turned into position for the collar u^1 to be acted upon by the cam faces f^1 a cylindrical tube 1 of a diameter only slightly exceeding those of the collars v, y can be applied to them and will become held firmly upon them as the resilience of the plates α causes the arms or fingers α^2 to move outwards when the spindle or axis d is being moved back into the position in which it is shown in Fig. 10. In the movement of the axis or stud d from the position in which it is shown in Fig. 11 to the position in which the collar u^1 is moved by the cam surfaces f^1 away from the conical surface p^2 , the cylindrical tube 1 applied around the collars v, y will be released by the plates α .

Fig. 13 shows another holder for cylindrical tubes. In the holder shown in Fig. 13 an axle i adapted to be revolved in bearings or guides is furnished with two collars 2 screwed on to screw-threads on the axle i and secured in position upon it by set-screws 3 and provided with cylindrical circumferential parts and also with bevelled edges 2^a and disposed so that the bevelled parts 2^a are directed oppositely away from one another. Two plates or whorls α similar to those shown in Figs. 1 and 2 but of smaller diameter and made in their unstressed condition to present the tips of their arms or fingers α^2 in diametral extension a little less than or approximately equal to those of the collars v, y are applied around the axis or spindle i and made to present their dished or hollowed faces respectively to the bevelled parts of the two collars. Two nuts 4 with milled heads screwed upon the screw-threads of the axle or spindle i are provided to bear against the central collars α^1 of the plates or whorls α so that when a cylindrical tube 1 of a diameter slightly exceeding that of the collars v, y has been placed around them the nuts 4 being screwed in opposite directions towards one another, may be made to press upon the collars α^1 of the plates α and, by flattening the plates α , to press the arms α^2 into engagement with the tube 1 to hold it firmly in position on the collars 2 or may be screwed in opposite directions away from one another to release the plates α from pressure so that the resilience of the plates α may retract the arms α^2 and release the tube.

In carrying this invention into effect, plates or whorls may be formed with arms or fingers in any number even or odd whether such arms or fingers be of equal or un-

equal radial extension and whether or not the arms in the stressed or unstressed condition diverge by equal extents or angles or different extents or angles from the plane or surface of reference.

It is to be understood that variations in detail may be made in carrying this invention into effect in the provision of whorls or plates and also in the construction and mounting of the spindles or holders in which they are to be applied according to the condition of use and the functions to be performed.

What I do claim as my invention and desire to secure by Letters Patent is:

1. A tube holder comprising a spindle, a dished resilient metal plate thereon, relatively fixed and axially movable collars on the spindle, said collars engaging the plate upon opposite sides thereof and at different distances from its center, and means for actuating the movable collar to cause the periphery of the plate to engage and release the tube.

2. A tube holder comprising a spindle, a dished resilient metal plate thereon, relatively fixed and axially movable collars on the spindle, said collars engaging the plate upon opposite sides thereof and at different distances from its center, and means for actuating the movable collar to cause the periphery of the plate to engage and release the tube, the periphery of the relatively fixed collar being beveled on its plate engaging side.

3. A tube holder comprising a spindle, a dished resilient metal plate thereon having longer and shorter arms projecting from the plate in different planes, relatively fixed and axially movable collars on the spindle, said collars engaging the shorter arms and central portion of the plate respectively upon opposite sides thereof and at different distances from its center, and means for actuating the movable collar to cause the longer arms of the plate to engage and release the tube.

4. A tube holder comprising a spindle, a dished resilient metal plate thereon having longer and shorter arms projecting from the plate in different planes, relatively fixed and axially movable collars on the spindle, said collars engaging the shorter arms and central portion of the plate respectively upon opposite sides thereof and at different distances from its center, and means for actuating the movable collar to cause the longer arms of the plate to engage and release the tube, the periphery of the relatively fixed collar being beveled on its plate engaging side.

5. A tube holder comprising a spindle, a block thereon for engaging the inner wall of a conical tube at its smaller end, a dished resilient metal plate on the spindle at the larger end of the tube, relatively fixed and

axially movable collars on the spindle, said collars engaging the plate upon opposite sides thereof and at different distances from its center, and means for actuating the movable collar for causing the periphery of the plate to engage and release the tube.

6. A tube holder comprising a spindle, a block thereon for engaging the inner wall of a conical tube at its smaller end, a dished resilient metal plate on the spindle at the larger end of the tube, relatively fixed and axially movable collars on the spindle, said collars engaging the plate upon opposite sides thereof and at different distances from its center, and means for actuating the movable collar for causing the periphery of the plate to engage and release the tube, the periphery of the relatively fixed collar being beveled on its plate engaging side.
- 20 7. A tube holder comprising a spindle, a block thereon for engaging the inner wall of a conical tube at its smaller end, a dished resilient metal plate on the spindle at the larger end of the tube, said plate having longer and shorter arms projecting therefrom in different planes, relatively fixed and axially movable collars on the spindle, said collars engaging the shorter arms and cen-

tral portion of the plate respectively upon opposite sides thereof and at different distances from its center, and means for actuating the movable collar for causing the longer arms of the plate to engage and release the tube.

20 8. A tube holder comprising a spindle, a block thereon for engaging the inner wall of a conical tube at its smaller end, a dished resilient metal plate on the spindle at the larger end of the tube, said plate having longer and shorter arms projecting therefrom in different planes, relatively fixed and axially movable collars on the spindle, said collars engaging the shorter arms and central portion of the plate respectively upon opposite sides thereof and at different distances from its center, and means for actuating the movable collar for causing the longer arms of the plate to engage and release the tube, the periphery of the relatively fixed collar being beveled on its plate engaging side.

In testimony, that I claim the foregoing as my invention, I have signed my name this 25 seventh day of December 1928.

GRINDROD KERSHAW.
